UNITED STATES PATENT OFFICE.

NILS H. ANDERSON, OF MIDDLETOWN, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,120,660.

Specification of Letters Patent. Patented Dec. 15, 1914.

Application filed April 13, 1910. Serial No. 555,132.

To all whom it may concern:

Be it known that I, NILS H. ANDERSON, a citizen of the United States, residing at Middletown, in the county of Middlesex and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and with regard to the more specific features thereof, to line lock and margin release mechanism therefor.

One of the objects of the present invention is to provide a mechanism of the above character which will be practical and efficient in operation.

Another object is to provide an apparatus of the above nature which will be simple in construction and arrangement of parts and cheap to manufacture.

A further object is to provide a device of the above nature which will co-act with the parts built for and subjected to the greatest strain, thereby being more reliable in its action, and having a less tendency to get out of order or break and strain the weaker parts.

A further object is to provide a mechanism of the above character adapted to relieve the strain imposed on the locking member by actuation when not in the proper relative position to enable it to move to a locking position.

A further object is to provide a construction of the above nature which will be substantially noiseless in its operation, and in which the movable parts are returned to normal position in a silent manner without impact or concussion.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of the many possible embodiments of this invention, Figure 1 is a side

elevation of part of a typewriting machine sufficient to illustrate the invention as applied thereto; Fig. 2 is a plan view of the same, partly in section; and Fig. 3 is a rear elevation, partly in section, with parts removed for the sake of clearness.

Similar reference characters refer to similar parts throughout the several views of the drawings.

In the accompanying drawings, the invention is shown as applied to that form of the machine known as the "Noiseless typewriter," but it is, of course, to be understood that the invention herein shown and described is not to be limited to its present application for it is obvious that the construction could be applied to many classes of typewriting machines without material alterations.

Referring to these drawings in detail, 1 denotes a base of the frame of a typewriting machine, on the upper part of which is mounted a reciprocating carriage 2 adapted to have a sliding contact with a rear abutment 3, or what is familiarly known as the center tie, whereby the carriage may be adjusted relatively to the end of the normal stroke of the type carriers to accommodate the varying number of sheets of paper carried thereby, all in a well known manner. In this center tie 3 is placed a line lock lever 4 pivotally mounted in vertically disposed trunnions 5 carried by a block 6 secured to a shaft 7 mounted in bearing lugs 8 on the center tie. One end of this lever 4 projects upwardly within the center tie 3, and has a forwardly bent portion 9 adapted to be engaged by stops 10 or 11 on the carriage 2 when moved in opposite directions. These stops 10 and 11 may be of any suitable form and construction movable with the carriage and capable of longitudinal adjustment along a rail 12 as desired, each being provided with a plane face 13 adapted to co-act with the part 9 of the line lock lever 4, and a beveled face 14 against which the line lock lever co-acts in returning to normal position, as will be more fully hereinafter explained. The opposite end 15 of the line lock lever 4 extends forwardly in the frame and is held between two pivoted jaws 16 and 17 mounted on a transversely disposed longitudinally movable locking bar 18. These jaws 16 and 17 are

held adjacent the sides of the line lock lever by means of a connecting spring 19 and their movement toward each other is limited by projecting lugs 20 engaging pins 5. 21 on the line locking bar. This locking bar is supported at each end from ears 22 projecting from the inner side of the frame, having a stud 23 co-acting with a longitudinal slot 24 in the bar. On one ear 22 10 is mounted a pin 25 to which is attached one end of a spring 26, secured at the other end to a lug on the locking bar 18 for holding the same in normal or unlocked position, as is clearly shown in Fig. 3. The ends 27 15 of the locking bar 18 are bent at right angles thereto and provided with pads 28 for insuring a noiseless movement in either direction.

From the lower side of the locking bar 20 depend two hooks 29 and 30 adapted, when the bar is moved to the left (Fig. 3), to engage under arms or projections 31 and 32 rigidly secured near opposite ends of a universal rock shaft 33 mounted on pivot points 25 34 projecting from the inner sides of the frame. Pivotaly suspended from the ends of these arms are connecting links 35 and 36 supporting a universal bar 37 on which rest key levers 38. The universal bar and key 30 levers may be of any well known construction, the former having a suitable pad 39 on the upper surface thereof to prevent noise, and the latter moving in a comb 40 at the forward end, and held against a knife 35 edge 41 at the rear end. It is thus seen that the locking means directly engages the arms 31 and 32 supporting the universal bar on which all of the strain is applied when operating against the line lock mechanism.

40 Referring now to the margin release mechanism, the shaft 7 carrying the block 6 and trunnions 5 in which the line lock lever 4 is mounted, extends to one side of the frame and has rigidly secured thereon an arm 42 having a rounded end 43 adapted to engage a flat portion 44 of a key lever 45 pivoted on a stud 46 and held in normal position by means of a spring 47. It is thus seen that when the key lever 45 is depressed, 50 rotating about the pivot stud 46 on which it is mounted, the rear end thereof will be raised to rotate the shaft 7 against the tension of a spring 48 thereon, thereby carrying the line lock lever 4 away from the path 55 of travel of the stops, permitting the carriage to move farther toward the end of the frame to receive additional printing. On releasing the key 45, the various springs 26, 47 and 48 will tend to restore the parts to 60 normal position.

The operation of this apparatus is substantially as follows: Assuming the machine to be in operation and the carriage traveling from right to left in its normal course of operation, the plain surface 13 of the line

lock stop 11 carried usually at one end of the carriage, contacts with the bent over end 9 at the upper part of the line locking lever 4, swinging the same about vertically disposed pivots or trunnions 5, as clearly shown in Fig. 2. The opposite end of this lever contacts with the jaw 16 pivotally mounted on the locking bar 18 and as the spring 19 is stronger than the spring 26 between the pin 25 and the locking bar, the locking bar will be carried to the left a sufficient distance to permit the hooks 29 and 30 carried thereby to engage with the arms 31 and 32 on the universal rock shaft. As these arms support the universal bar, a movement of the latter is prevented on striking of a key and the machine is thereby locked against further operation until the margin release mechanism is actuated by pressing the margin release key. The shaft 7 on which the trunnion for the line lock lever is mounted is rotated so as to carry the line lock lever rearwardly out of the path of the stop 11. As soon as the end of the line lock lever escapes from the plain surface 13 of the line stop it is swung laterally into the plane of normal position by means of the spring 26 on the locking bar engaging the opposite end 15 thereof, and the spring 48 on the shaft 7 rotates the trunnions 5 in which the line lock lever is mounted so that the upper end 9 of the line lock lever is carried forwardly into engagement with the beveled surface 14 of the stop 11 where it slides into normal position on the next spacing of the carriage, after which the carriage may continue in its movement until it reaches the end of its possible path of travel.

Should the machine be operated under such conditions that the universal bar was depressed at the moment of contact between the margin stop and the upper end of the line lever, so that a lateral movement of the locking bar 18 was prevented by the reason of the fact that the lower part of the hooks 29 and 30 carried thereby engaged the arms 31 and 32, the spring 19 holding the jaws 16 and 17 adjacent the opposite end of the line lock bar would yield, thereby preventing any strain upon the movable parts. As soon, however, as the universal bar was released the arms 31 and 32 carried by the universal rock shaft would be returned to normal position, and the spring 19 acting on the jaw 16 would tend to carry the locking lever 18 into position to engage the hooks carried thereby with the arms, thereby locking the machine against further operation. The lower part of the hooks 29 and 30 and the upper part of the arms 31 and 32 are rounded to permit easy action. The margin stop 10, which is also carried by the carriage and is for the purpose of determining the marginal line at the left of the sheet, will not, of course, actuate the line locking mecha-

nism, but merely engages with the upper part of the line locking lever and presses the spring within a buffer 49, Fig. 3, arresting the carriage at the desired point. Should, however, it be desired to write upon the margin, such as a line number, for example, the margin release key 45 may be depressed to carry the line locking lever out of engagement with the margin stop 10, wherefore by the carriage can be given a further movement to the right. The opposite end 15 of the line lock lever normally engages the spring held jaw 17 which yields under the movement of the lever when engaged by the carriage on its return to a line commencing position to prevent breakage or springing of the parts.

It is thus seen that this invention provides for a practical and efficient mechanism of the character above described accomplishing, among others, the objects and possessing the advantages herein set forth. It is to be noted that the arrangement of the springs, pads, and yielding parts throughout the mechanism permits a silent operation of the device without in any way affecting its efficiency or quickness of operation.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, a plurality of finger actuated members, a universal bar mechanism in operative relation thereto, a carriage, a margin stop carried thereby, and a pivoted member positioned fore and aft of the machine adapted to be engaged by said stop at its rear end and operate upon the universal bar mechanism at the forward end to prevent operation thereof as the finger actuated members are moved.

2. In a typewriting machine, in combination, a frame, a carriage movable relatively thereto, a universal rock shaft, a universal bar operatively associated therewith positioned beneath the key levers at the forward part of the machine, and means for locking the universal bar against movement, including a longitudinally disposed pivotally supported bar adapted to be engaged at one end by the carriage to prevent a movement of the universal bar by its other end.

3. In a typewriting machine, in combination, a carriage, an adjustable stop carried thereby, a key-lever, a member adapted to be actuated at each impression thereof, a

lever extending fore and aft of the machine from a point behind the carriage to a point adjacent the member actuated by the key-lever, and a part adapted to be moved transversely of the machine by said lever to lock 70 said member and key-lever against movement.

4. In a typewriting machine, in combination, a reciprocating carriage, a rock shaft, arms supported by said rock shaft, a longitudinally movable bar transversely mounted on the machine adapted to engage with said arms, and means positioned fore and aft of the machine through the central part thereof adapted to be actuated by the carriage at 75 one end and adapted to actuate said movable bar near its other end to lock said arms and rock shaft against movement.

5. In a typewriting machine, in combination, a carriage, a relatively fixed member 85 centrally disposed on the frame of the machine and positioned behind said carriage, a universal rock shaft, and intermediate mechanism between the carriage and said rock shaft partially supported by said member 90 adapted when engaged by the former to lock the latter against movement.

6. In a typewriting machine, in combination, a carriage, an abutment positioned behind said carriage, a universal rock shaft, a 95 projection on said shaft, means adapted to engage said projection, and intermediate mechanism partially supported on said abutment adapted to be actuated by said carriage on engagement therewith to lock said rock 100 shaft against movement.

7. In a typewriting machine, in combination, a reciprocating carriage, a movable member, locking means therefor adapted to be moved into engagement with the same 105 when in normal position, means for actuating said locking means, and spring held pivotally mounted means mounted on said locking member adapted to yield and relieve the strain on said locking member when the 110 movable member is in a position to obstruct its movement and prevent its locking action.

8. In a typewriting machine, in combination, a reciprocating carriage, a universal rock shaft, arms on said rock shaft, a universal bar supported by said arms, a locking member adapted to engage said arms when in normal position, intermediate means between said locking member and the carriage for actuating the former when engaged by the latter, and pivoted spring held arms on said locking member engaged by said intermediate mechanism adapted to yield when movement of the locking member is obstructed as when the arms are out of normal 125 position.

9. In a typewriting machine, in combination, a reciprocating carriage, a rock shaft, means adapted to lock said rock shaft again movement when the carriage reaches 130

the end of a line, including endwise movable bar for locking said rock shaft and a universally supported lever for actuating said bar, and mechanism adapted to release 5 said locking means when it is desired to add extra letters.

10. In a typewriting machine, in combination, a reciprocating carriage, a universal bar, locking mechanism for said universal 10 bar, including a longitudinally movable bar, and intermediate mechanism between the carriage and the locking means including a universally pivoted bar adapted to rotate about one set of pivots to actuate said locking means and adapted to be rotated about the other set of pivots to release said locking 15 means.

11. In a typewriting machine, in combination, a reciprocating carriage, a movable 20 member, a longitudinally movable lock bar for said member, intermediate mechanism between said carriage and said bar including a universally mounted bar adapted to be rotated about one axis for actuating the 25 locking mechanism and about another axis for releasing the same.

12. In a typewriting machine, in combination, a reciprocating carriage, a plurality of stops thereon, a movable member, locking 30 means for said member, including an endwise movable bar and a pivotally mounted lever at right angles thereto having one end engaging said bar, mechanism adapted to be engaged by said stops to actuate said locking means when the carriage reaches one end of a line, and mechanism for releasing said locking means whereby the carriage may be given a further movement.

13. In a typewriting machine, in combination, a reciprocating carriage, a movable 40 member, locking means therefor, means adapted to actuate said locking means when engaged by said carriage, said means including a universally pivoted bar, an arm 45 projecting from the pivot bearings, and key operated means adapted to engage said arm to move the bearings whereby the locking means is released.

14. In a typewriting machine, in combination, a reciprocating carriage, a movable member, locking means therefor, means adapted to actuate said locking means, including a universally pivoted longitudinally disposed lever, an arm projecting

from the bearings thereof, and a pivotally 55 mounted key lever adapted to engage said arm to rotate said bar about its pivots whereby the locking means is released.

15. In a typewriting machine, in combination, a reciprocating carriage, a movable 60 member, locking means therefor, means adapted to actuate said locking means, including a universally pivoted longitudinally disposed lever, an arm projecting from the bearings thereof, and means for 65 returning said bar into normal position.

16. In a typewriting machine, in combination, a reciprocating carriage, a stop thereon having oppositely disposed plain and beveled faces, a movable member, locking 70 means therefor, means adapted to be engaged by the plain face of said margin stop to actuate said locking means, and means adapted to move said actuating means laterally away from said stop for releasing 75 said locking means.

17. In a typewriting machine, in combination, a reciprocating carriage, a margin stop thereon having oppositely disposed plain and beveled faces, a movable member, locking 80 means therefor, means adapted to be engaged by the plain face of said margin stop to actuate said locking means, means adapted to move said actuating means laterally away from said margin stop for releasing 85 said locking means, and means for further moving said actuating means at right angles to its first movement whereby it engages the inclined face of said margin stop and returns it to normal position. 90

18. In a typewriting machine, in combination, a reciprocating carriage, a stop thereon having oppositely disposed plain and beveled faces, a movable member, locking 95 means therefor, means adapted to be engaged by the plain face of said stop to actuate said locking means, means for further moving said actuating means at right angles to its first movement whereby it engages the inclined face of said stop and 100 returns it to normal position, and means for limiting its latter movement.

In testimony whereof I affix my signature, in the presence of two witnesses.

NILS H. ANDERSON.
